UNITED STATES PATENT OFFICE.

FRANÇOIS A. NOUSSAT, OF LIMOGES, FRANCE, ASSIGNOR TO FRANCIS H. BAWO AND CHARLES T. DOTTER, OF NEW YORK, N. Y.

DESIGN FOR TABLE-WARE.

SPECIFICATION forming part of Design No. 16,062, dated April 28, 1885.

Application filed March 16, 1885. Term of patent 7 years.

To all whom it may concern:

Be it known that I, FRANÇOIS ADOLPHE NOUSSAT, of Limoges, France, Rue Cruveilher No. 2, have invented and produced a certain new and original Design for Table-Ware, 5 of which the following is a specification.

This design relates to dishes, plates, &c., such as are generally used for the table.

The accompanying drawing illustrates a 10 plate embodying my design.

A designates a plate which I have selected as an example of table-ware embodying my design. It has a rim-like portion, *a*, and a depressed central portion, *a'*. Arranged upon 15 the rim-like portion outward from the depressed portion is a fanciful design, B, which, as here shown, extends approximately in the form of a rectangle, although it has not rectangular corners. That portion of said design 20 which is nearer the depressed portion *a'* is striated or fluted, as at *b*. Beyond the striated or fluted portion *b* is a portion, *b'*, representing conventionalized fleur-de-lis.

This design is applicable to dishes presenting rectangular or oblong outlines, as well as 25 those of circular outline, and it may be arranged upon the covers of dishes as well as upon the dishes themselves. It may be colored to contrast with the color of the dish, if desirable. 30

What I claim as my design, and desire to secure by Letters Patent, is—

1. The design for a piece of table-ware, consisting of a figure extending approximately in the form of a rectangle about the same, and 35 consisting of a striated or fluted portion and representations of fleur-de-lis, substantially as shown and described.

2. The design for a piece of table-ware, consisting of the fleur-de-lis *b'* and the striated or fluted portion *b*, substantially as specified. 40
